REFRIGERATOR STRUCTURE

Tracy D. Montee, Rizal Province,
Philippine Islands

Application March 9, 1934, Serial No. 714,871

6 Claims. (Cl. 62—95)

This invention relates to refrigerators and more particularly to a construction whereby heat absorbing fluid may be circulated through brine tubes and effect cooling of the brine and atmosphere about the brine tubes.

Another object of the invention is to so arrange the brine tubes that their ends will be connected by headers and together with the headers form a device which may be supported in a horizontal 10 position and employed as a shelf in a counter or chamber of a refrigerator.

Another object of the invention is to provide an improved type of fluid circulating coil having its convolutions arranged in the form of a spiral and 15 the convolutions staggered with respect to each other thereby providing a coil which may be disposed in flat brine tubes spaced transversely from each other.

Another object of the invention is to so arrange 20 the convolutions of the fluid circulating coil that as fluid moves through the convolutions brine in tubes spaced transversely from each other by a number of such tubes will be successively cooled thereby causing the cooling action to be evenly 25 distributed and a very effective cooling action to take place.

Another object of the invention is to provide 30 improved means for connecting the headers with end portions of the brine tubes and provide a very strong construction which will not be liable to leak.

Still another object of the invention resides in 35 providing a construction which is simple and durable, inexpensive to manufacture and which will be very efficient in use.

With these and numerous other objects in view, my invention consists in the novel features of construction, combination and arrangement of parts as will be hereinafter referred to and more 40 particularly pointed out in the specification and claims.

The invention is illustrated in the accompanying drawings wherein:—

Figure 1 is a top plan view of a refrigerator 45 shelf formed in accordance with this invention.

Figure 2 is a side elevation of the shelf.

Figure 3 is a sectional view taken through one header along the line 3—3 of Figure 1.

Figure 4 is a similar view taken through the other header along the line 4—4 of Figure 1.

Figure 5 is a sectional view taken longitudinally through the shelf along the line 5—5 of Figure 2 with the inner coil shown in top plan.

Figure 6 is a fragmentary sectional view upon

an enlarged scale taken along the line 6—6 of Figure 1.

Figure 7 is a fragmentary view looking at one end of the shelf, the view being taken along the line 7—7 of Figure 1.

This improved device consists of a number of brine tubes each formed of strong sheet metal. These tubes are rectangular in cross section in order to provide flat upper surfaces for the tubes and therefore a number of these tubes disposed in 10

spaced parallel relation to each other may form a portion of a shelf having a flat upper surface and articles may be set in place thereon without being liable to turn over. Ends of the tubes are connected by bridging members 2 which are also 15

of sheet metal and may be united to ends of the tubes in any desired manner. These bridges extend transversely of the tube and are open along their outer sides as shown clearly in Figures 5 and 6 in order that access to ends of the tubes may 20 be had through the bridging members. Collars 3 of sheet metal fit snugly about the bridges where they are firmly secured by solder 4 or spot welding and portions of these collars project from the bridges in order to fit snugly within headers 25

5 and 6 where they are secured by solder as shown at 7 or 8 or by spot welding. The headers are closed except along their inner sides through which the collars extend and therefore brine is 30 poured inwardly through threaded openings 9 formed in the header 5 may flow from this header through the brine tubes into the header 6 and cause both of the headers and all of the tubes to be completely filled with brine. The openings 9 35 may be closed by threaded plugs 10 or pipes leading from a source of brine or to headers of other units engaged in these openings.

In order to cool the brine there has been provided a coil formed of tubing which may be of any diameter desired and may be a single length 40 of flexible tubing bent to form convolutions or separate tubes suitably connected by elbows or other couplings to form the convolutions. Referring to Figures 3, 4 and 5 it will be seen that the coil consists of a determined number of convolutions which are arranged in spiral formation and staggered transversely of each other. Longitudinally extending side portions 12 and 13 of each convolution extend longitudinally through a pair

of brine tubes with their ends projecting through 50 the bridges and collars into the heads 5 and 6 where they are connected by end portions 14 and 15 extending longitudinally in the headers. The side portions 12 and 13 of each convolution extend

through brine tubes spaced from each other by a 55

number of other brine tubes as clearly shown in Figures 3 and 4 and therefore heat absorbing fluid circulated through the coil will first pass through the side portion 12 of a convolution extending 5 through the first brine tube at one side of the shelf and will then pass through the end portion 14 of this convolution and back through the side portion 13 extending through a brine tube at approximately the transverse center of the shelf 10 which in the present illustration is brine tube number 6 counting from the bottom of Figure 5. From this tube the fluid passes through the end portion 15 of the convolution until it reaches the side portion 12 of the second convolution and 15 through this side portion which is located in the second brine tube. The end portion 14 of this convolution extends through the header 5 above the end portion 14 of the first convolution as shown in Figure 3 and the side portion 13 of this 20 convolution passes through brine tube number 7. This staggered arrangement of the convolutions is repeated throughout the width of the shelf and due to this arrangement of the convolutions the cooling action which takes place as the heat absorbing gas is circulated will be evenly distributed 25 throughout the width of the shelf and the brine in the brine tubes and headers remain at substantially an even temperature. The side portion 12 of the first convolution and side portion 13 of the 30 last convolution extend through end portions of the header 6 transversely thereof and each of these portions extends outwardly through the outer side wall of the header for connection with a circulating system for the fluid. Leakage of 35 brine must be prevented and in order to do so there has been provided packing glands 16 each consisting of a cup 17 riveted or otherwise firmly secured against the outer side wall of the header and projecting inwardly about the tubing as 40 shown in Figure 6. This cup receives packing 18 and is internally threaded for engagement with the threads of a sleeve 19 which when screwed inwardly forces the packing tightly into the inner end of the cup about the tube and forms a very 45 tight joint. It will of course be obvious that the tubing for circulating the heat absorbing fluid must be assembled in the brine tubes before the headers 5 and 6 are set in place and secured to the collar 3.

50 From the foregoing description of the construction of my improved apparatus, the application of the same to use will be readily understood. It will be seen that I have provided a simple, inexpensive and efficient means for carrying out 55 the objects of the invention.

While I have particularly described the elements best adapted to perform the function set forth, it is obvious that various changes in form, proportion and in the minor details of construction may 60 be resorted to without departing from the spirit or sacrificing any of the principles of the invention.

Having thus described the invention what is claimed is:

1. In a refrigerator structure, a plurality of brine tubes spaced transversely from each other and having flat upper side faces, headers extending transversely of the tubes and connected with the tubes with ends of the tubes opening into the headers, the headers and tubes forming a shelf having end portions adapted to rest upon supports, and a coil for circulating heat absorbing fluid extending through the brine tubes and headers and having end portions projecting outwardly for connection with a circulating system, the portions of the coil extending through the headers being disposed longitudinally thereof in overlapped relation to each other. 5
2. In a refrigerator structure, a plurality of 15 brine tubes, heads extending transversely of said tubes and connected with ends of the tubes, and a coil for circulating heat absorbing fluid through the tubes and heads having its convolutions arranged in spiral formation and in stepped relation 20 transversely of each other.
3. In a refrigerator structure, a plurality of brine tubes, heads extending transversely of said tubes and connected with ends of the tubes, and a coil for circulating heat absorbing fluid through 25 the tubes and heads having its convolutions arranged in stepped relation transversely of each other and each after passing through a brine tube extending longitudinally in a head past a plurality of the brine tubes and back through a brine 30 tube to the other head.
4. In a refrigerator construction, a plurality of brine tubes spaced transversely from each other, bridges connecting ends of said tubes, headers extending transversely of the tubes and connected 35 with the bridges for communication with the tubes, and a coil for circulating heat absorbing fluid having its convolutions extending through the tubes and headers. 40
5. In a refrigerator construction, a plurality of brine tubes spaced transversely from each other, bridges connecting ends of said tubes, collars secured about said bridges and projecting from the same, headers secured about the collars and communicating with the tubes through the collars and 45 bridges, and a coil for circulating heat absorbing fluid having portions extending through the tubes and connected by portions extending longitudinally in the headers. 50
6. In a refrigerator construction, a plurality of brine tubes spaced transversely from each other, bridges connecting ends of said tubes, collars secured about said bridges and projecting from the same, headers secured about the collars and communicating with the tubes through the collars and 55 bridges, and a coil for circulating heat absorbing fluid having its convolutions arranged in stepped relation transversely of each other and each having portions extending through a pair of tubes and connected by portions extending longitudinally in the headers in crossed relation to a plurality of tubes between the said pair of tubes. 60

TRACY D. MONTEE.
